The ornamental design for a pillar device for insect capture with guards, as shown and described.

DESCRIPTION

FIG. 1 is an upper-front-right perspective view of a pillar device for insect capture with guards, according to our new design;

FIG. 2 is a front view of the pillar device for insect capture with guards shown in FIG. 1, which is the same as the rear view;

FIG. 3 is a top plan view of the pillar device for insect capture with guards shown in FIG. 1, which is the same as the bottom plan view;

FIG. 4 is a perspective sectional view of the pillar device for insect capture with guards through section 4-4 indicated in FIG. 1; and,

FIG. 5 is a perspective sectional view of the pillar device for insect capture with guards through section 5-5 indicated in FIG. 1.

The broken line showing of top and bottom hanging features is for the purpose of illustrating portions of the pillar and forms no part in the claimed design.
